UNITED STATES PATENT OFFICE.

ALEXANDER G. ROTINOFF, OF NEW YORK, N. Y.

FILE.

Application filed August 4, 1924. Serial No. 729,890.

This invention relates to piles built in situ.

According to the existing methods of building piles of this kind, the hole is generally driven first and then filled with concrete. In order to protect the hole from collapsing during and between these two operations many different expedients are employed. In some systems a shell is driven into the ground and then filled with concrete, the shell being left permanently in the ground as part of the pile. The cost of the shells and of the special appliances for driving them add considerably to the cost of the piles. In other systems a heavy driving tube is used as a temporary casing which is gradually withdrawn as the concrete is fed through it. These systems necessitate a very powerful plant and the operations are slow and costly.

The principal object of the present invention is to simplify and cheapen the construction of piles of this kind, at the same time maintaining or even increasing the reliability and efficiency of the piles.

A further object of the present invention is to provide a method of building piles in situ, whereby the use of permanent shells, temporary casings and like protections during concreting may be avoided.

A further object is to provide a method of driving the material which constitutes the pile into the ground in direct contact with the surrounding soil.

A further object is to provide a method of building piles in situ, in which the hole in the ground is at once filled in under pressure with concrete or other pile-forming substance, so that the static pressure of the soil and water are immediately counterbalanced by the pressure of the introduced concrete or the like and no third element or other mechanical device has to be utilized to prevent the walls from collapsing.

Another object is to provide means whereby piles may be built in situ and may be consolidated during and after driving by positively forcing or tamping the concrete or the like into the hole in the ground in which it is to be located.

A further object is to provide a new and valuable method of producing reinforced piles in situ.

Further objects will become apparent

from the following description and drawings, in which—

Fig. 1 is a section of a pile during building illustrating a method of building a pile in situ.

Fig. 2 is a side elevation of the mechanism shown in Fig. 1.

Fig. 3 is a cross-sectional view on the line 3—3 of Fig. 2, illustrating a manner in which the concrete forcing mechanism may be driven, and the manner in which the head of the driving member is guided.

Fig. 4 is a plan view of the shoe and reinforcing bars shown in Fig. 1.

Fig. 5 is a section of the completely driven pile already shown in Fig. 1, illustrating the manner in which the driving tool is withdrawn by rotation and the concrete or filling material consolidated.

Fig. 6 is a section of a pile illustrating the manner in which a tapered pile may be built.

Fig. 7 is a view similar to Fig. 6 illustrating the manner in which the driving member is withdrawn, and the concrete forced into place.

Fig. 8 is a section of a pile illustrating a somewhat different form of shoe and forcing screw.

Fig. 9 is a view similar to Fig. 8 illustrating the manner in which the concrete is forced inwardly during withdrawal of the driving member, and the production of an enlargement or pedestal near the base of the pile.

In the embodiment of the invention illustrated in Figs. 1 to 5, 1 is a driving member or tool of sufficient strength to take the driving impacts. 2 is a shoe which may be of cast iron or other suitable material. The driving member 1 is removably connected to the shoe 2, for example by being inserted into a recess 3 therein, so that the driving impacts are communicated to the shoe while driving and the driving member can be readily withdrawn when driving is completed.

8 is a metal ring which is driven into the ground for a short distance, so as to constitute a collar on the finished pile which may or may not be removed when the pile is finished. During driving the ring 8 defines a feeding orifice for the incoming concrete and protects the edge of the hole. The hopper 4 is located around the driving member 1 and is adapted to feed concrete into the orifice

constituted by the ring 8, the concrete being fed into the hopper 4 by the chute 5.

In driving the pile the ring 8 is first inserted into the ground and the shoe 2 is positioned inside the ring 8. The hopper 4 is placed in position over the ring 8 and the lower end of the driving member 1 is inserted in the recess 3 of the shoe. The driving may be effected by any ordinary pile driving mechanism acting on the driving member 1 instead of the usual pile. When driving is commenced the hopper 4 is supplied with fairly liquid concrete from the chute 5 and as the shoe 2 is driven into the earth the concrete 6 by its own gravity follows and fills up the resulting hole 7. The chute 5 may be directly connected with a concrete mixer and since the hopper 4 is located at the ground level, no labor is required for transporting or hoisting the concrete from the mixer to the pile hole.

In this modification the driving member 1 is provided with a screw or conveyer 9 between the threads of which the concrete from hopper 4 enters, so that as the screw is driven downwards by impacts, it forces the filling material into the hole by ramming action. The driving member 1 is preferably removably attached, for example by means of a left handed screw thread 10 to a driving head 11, carrying the usual dolly 12 of wood for receiving the driving impacts from the driving monkey 13. The driving head 11 is carried in a collar 14 connected with sliding members 15 carried in slides 16 which are supported by upright guides 17 forming part of the pile driving derrick. The driving head 11 is provided with a bevel gear 18 adapted to be rotated by means of a bevel pinion 19, mounted on a shaft 20 supported in bearings on a projecting part of the collar 14. The shaft 20 can be driven in any suitable manner, for example by an electric motor 22, acting through a train of gears 23, 24, 25 and 26. In operating this apparatus the shoe 2 is driven into the ground and the driving member 1 is preferably simultaneously rotated in the unscrewing direction so as to feed positively the concrete into position by the action of the screw 9. In some cases the member 1 may only be rotated after the shoe has been driven to the necessary depth when the driving member has to be withdrawn. Fig. 5 illustrates the withdrawal of the driving member 1 and it will be readily understood that by rotation of the driving member 1 the concrete is fed inwardly to take its place and to cause a perfectly consolidated pile to be left in the ground.

Effective consolidation can also be effected by withdrawing the screw a little and then imparting one or more driving impacts. This may be repeated several times at various stages of the withdrawal so that

a pile perfectly consolidated throughout its length is ensured. It is to be noted that the withdrawal of the screw can readily be effected by rotating it so as to tend to unscrew it out of the concrete. The reaction of this rotation on the concrete is to impel and convey it inwardly to take the place of the driving member and screw as they are withdrawn and to fill in any cavities or fissures that may exist in the concrete.

In practice, the withdrawal of the screw and the consolidation of the material forming the pile is satisfactorily and automatically obtained by slowly rotating the screw in a direction to cause it to rise out of the pile. The motor 22 and connected gearing and the platform 14 and head 11 may be counterbalanced during the rotation of the wheel 18 for the withdrawal of the screw 9. By counter-balancing and by rotating the screw, the driving member 1 will start to rise out of the hole automatically against the reaction of compressed concrete when its reaction will overcome the weight of the driving member. As long as the hole 7 is incompletely filled or if there are cavities in the concrete or if the concrete has not been sufficiently consolidated, the rotating driving member will continue to propel the concrete from the hopper downwards and will not rise out of the pile. Such automatic control ensures the quality of the pile and the reliability of the method.

In Figs. 1 to 5, I have also illustrated the way in which reinforced piles can be produced according to the present invention. The reinforcement is preferably constructed of steel bars, expanded metal or wire framework 27 attached to webs 28 in the shoe. As the shoe is driven into the earth the reinforcement 27 is pulled after it and when a certain amount of concrete has been filled in, the shoe, reinforcement and concrete tend to move forward as a unit.

While I have shown the hopper 4 located on the ground, it may be attached to the pile driving derrick, since the hopper is always located directly under the pile driving monkey 13.

The modification shown in Figures 6 and 7 is adapted for the production of tapered piles. The driving member 1 is provided with a relatively long screw 29, preferably extending along the whole depth of the pile. The screw is of substantial size and is preferably provided on its under side with a beveled portion 30. This modification is illustrated in conjunction with a light shoe 31 but such a shoe may be omitted since the screw itself will drive a suitable hole in the ground for reception of concrete. In building the pile the driving member is driven by impacts into the earth through a hopper of concrete 4 so that the screw 29 carries concrete with it into the ground.

It is to be noted that in building piles of any length whatever all the concrete is fed at the ground level. As the screw is driven into the ground the beveled portions 30 thereof are forced against the earth and force it laterally for a short distance. As the driving continues the earth is thrust laterally in successive small amounts until the desired size of pile is attained. The presence of the concrete between the convolutions of the screw prevents the earth from collapsing into the space therebetween and the beveled portions 30 guide the earth outwardly as the driven member is forced into the earth. A small unscrewing movement is sufficient to release the screw from the shoe and hole and by rotating the screw the concrete is thrust inwardly and consolidated as shown in Figure 7. The methods of consolidating the pile, described in connection with the modification of Figs. 1 to 5, can likewise be applied in this modification.

In the modification shown in Figs. 8 and 9, the driving member 1 is shown with a short screw 40 of maximum diameter nearly as great as that of the finished pile. The radius of the screw diminishes rapidly toward the lower end and the shoe is a comparatively thin inverted dome shaped piece of thin sheet metal 41 which bears against the screw during driving. In this modification it is not necessary to rotate the screw during driving but when the shoe is driven sufficiently far into the ground the driving member is rotated and withdrawn, thereby forcing the concrete inwardly and the concrete is left in a consolidated state. Consolidation may also be effected in this modification by repeated impacts during withdrawal. This modification is very suitable for the production of pedestal piles, that is piles having enlargements such as is shown at 42 in Fig. 9. Such an enlargement is produced by partly withdrawing the driving member and applying a sufficient pressure thereto so that the concrete forces the earth outwardly and forms the enlargement at the desired part of the pile. In some cases it is sufficient to apply a dead pressure to the driving member. In other cases the enlargement is produced by impacts of the driving monkey. In this form it is advantageous that the lower face of the screw 40 should have an upward slope in the radial direction in order that the concrete may more readily be thrust outwardly against the wall of the hole 7.

It is, of course, to be understood that the present invention is readily applicable to the production of piles of different cross-section. For example by using square, rectangular or circular shoes, piles of corresponding cross-section are produced.

While I have given a number of detailed

constructions according to my invention I do not desire to be limited thereto since the invention may be modified in many directions without departing from the scope of the appended claims.

As an example of a further modification, I contemplate a modification in which the screw 9 is independent of the driving member 1, and shorter, so that the screw driving mechanism may have a stationary location in or adjacent the hopper 4 during driving, or the screw may be adapted to slide relatively to the driving member 1.

I also contemplate utilizing the invention for driving piles through a stratum of water 80 by extending the hopper 4 or the ring 8 through the layer of water.

In certain dry soils, it is possible to use this method for building piles with sand or fine gravel. I can also form composite piles 85 by this method, the lower part of sand or gravel and the upper part of concrete. I, therefore, do not intend to be limited to piles of concrete, but intend to include piles 90 of sand, gravel or other suitable building material.

I claim:

1. A method of building piles in situ which consists in forming the hole and simultaneously driving filling material into the hole 95 by the hole forming means.

2. A method of building piles in situ which consists in driving a tool into the earth and simultaneously driving, by the tool driving means, filling material into the hole 100 formed by the tool.

3. A method of building piles in situ which consists in driving a shoe step by step into the earth and simultaneously and continuously driving filling material into the hole 105 formed by the shoe.

4. A method of building piles in situ which consists in operating a tool through the pile forming material to carry the material into the earth and rotating the tool to withdraw the same and consolidate the pile. 110

5. A method of building piles in situ which consists in operating a tool through the pile forming material to fill and compress the same into the earth and rotating the tool to withdraw it and subjecting it to impacts during withdrawal to consolidate the pile. 115

6. A method of building piles in situ which consists in operating a tool by both blows and screwing to force it into the earth to form a hole and fill the same simultaneously, and consolidating the pile by the tool during its withdrawal from the hole. 120

7. A method of building piles in situ, 125 which consists in driving a hole into the earth, feeding and consolidating the filling material in the hole by rotating a screw therein during and after driving.

8. In pile building mechanism, means for 130

driving a hole into the ground and means co-operative therewith to force filling material into the said hole at the same time.

9. In pile building mechanism, means to form a hole in the ground and means co-operative therewith for feeding and forcing concrete down during the formation of the hole.

10. In pile building mechanism, means

adapted to form a hole by impacts into the ground and provided with spiral convolutions for carrying and driving concrete down into the hole, and means for causing rotation of the said convolutions.

In testimony whereof I affix my signature.

ALEXANDER G. ROTINOFF.
